UNITED STATES PATENT OFFICE.

JULES LOUIS BADEL, OF GENEVA, SWITZERLAND.

STRUCTURAL FRAMEWORK.

Application filed October 28, 1927, Serial No. 229,462, and in Belgium November 3, 1926.

My invention pertains to building constructions, and more particularly to supporting frame work therefor.

It is one object of my invention to provide a supporting frame for building construction that will permit of rapidity of erection with great strength and at a reduced cost over previous methods of construction.

It is a further object of my invention to provide a system of supporting frame work of sufficient lateral strength that no intermediate supports will be necessary even for great spans far in excess of that which is possible by present known methods of frame work construction.

It is a still further object of my invention to provide a system of frame work construction that will permit of the building of varying sized structures, there being but four different sized pieces of frame regardless of the size of the structure.

Briefly, the framing comprises a series of rectangles formed by overlapping long pieces, shorter joint covering pieces, spacing members forming sides of the rectangles and cross braces. The longer pieces abut end to end and overlap so that the bolts that hold the assembly together pass through the respective ends of the joint and the center of an adjacent piece. For additional strength, the open joint may be covered by a shorter joint-covering piece held by the same bolts. Spacing members may be secured in any well known manner between the above-described assemblies, but strength will be added to the structure if the spacing members abut against the ends of the cover joint pieces. However, with this arrangement, every other rectangle will be without a means for bracing the structure against lateral stresses. Accordingly, in every other rectangle is placed an ordinary cross brace, the members extending diagonally from one corner to the other. As a further means for strengthening the structure, long tie bolts may be provided extending from one of the assemblies to the other, and preferably passing through those rectangles in which the cross braces are located.

Other objects of my invention will be understood from the accompanying specification and drawings, wherein,

Figure 1 is a front sectional elevation of my invention as applied to a roof, such as an aviation hangar, parts being broken away to facilitate illustration, and

Figure 2 is a plan view thereof.

Referring to the drawings, the frame work is constituted by four elements cut to respective size to form a rectangle and the particular size of structure is accomplished by mere duplication of the rectangle. The size of the rectangles and therefore the size of the four pieces is predetermined in accordance with the stresses and strains which the particular structure is to withstand, it being the intent of this invention to provide a structure wherein no bracing members are provided at an angle thereto.

One of the rectangles is formed by walls *a*, *b*, *c* and *d*. Walls *b* and *d* extend beyond the walls *a* and *c*, as shown at *e*, *f*, *g* and *h*. The portions *e* and *g* abut against pieces *e'* and *g'* and the ends *f* and *h* abut against the pieces *f'* and *h'* respectively. The pieces *e'*, *f'*, *g'* and *h'* are exactly similar in size and length to the pieces *b* and *d*. Thus, the next adjacent rectangle to that formed by the walls *a*, *b*, *c* and *d* is formed by the portions *e*, *e'*, *g*, *g'*, respectively and a side wall *l* similar to the pieces *a* and *c*.

Overlapping the joint between the pieces *e* and *e'* is a second strip *d*² similar in size and length to the piece *d*. Thus the joint *e*, *e'* occurs in the center of the piece *d*². This arrangement is true of each of the joints. Accordingly, when bolts or other securing means *k* join together the pieces *d* and *d*², great strength is obtained by this overlapping of joints. This same arrangement occurs between joint *g* and *g'* where strip *b*² overlaps this joint.

One of the joints is always left exposed in diagonally opposite rectangles and these joints are covered by short pieces or strips *m* which are of a different length than the pieces *a* and *l*, but are adapted to abut thereagainst so as to give increased rigidity against lateral stresses to this particular rectangle.

In the rectangles which are not braced by the strips *m* are cross braces formed by strips *i* and *j* which extend diagonally from the corner formed by the pieces *a*, *d* to the corner formed by the pieces *b*, *c*. Thus, every rectangle is braced against lateral stresses, and all joints are well protected.

The cross braces *i* and *j* and the spacing strips *a*, *c* and *l* are secured in place by any well known means.

As a further means of strengthening the structure, tie bolts *n* may be used, between the horizontal extending assemblies of pieces *d* and *d*², *b* and *b*² respectively. The tie bolts

preferably extend through the rectangles containing the cross braces i , j and thus all parts of the assembly get full benefit of the result of using the tie bolts, since they pass through the pieces b , b^2 , d , d^2 , and the respective joint covering pieces m . It has been found sufficient to merely add two tie bolts in each rectangle containing a cross brace.

It is immaterial whether the pieces out of which this structure is formed are made of metal or of wood, and whether the securing members are bolts or rivets. The same rigidity of construction is obtained.

If the structure is to be arched such as the roof of an aviation hangar would be, the ends of the pieces d and b would be cut at an angle which would be a radius of the particular arc to be used in the construction so that the ends of the pieces would abut throughout their lengths and not at just one point thereon. If desired, the ends e and e' of each piece d or b may be tapered slightly as indicated in Figure 1. Also, if desired, the upper edge of the piece d and b may be cut on the same curve as the arc of the support, as indicated at o , but with a plurality of relatively small pieces, this is not essential.

Modifications may be made in the arrangement and location of parts within the spirit and scope of my invention, and such modifications are intended to be covered by the appended claims.

I claim:

1. Structural frame work comprising a plurality of assembled strips extending in one direction, each strip comprising a plurality of abutting and overlapping pieces so arranged that the joint between abutting ends occurs substantially at the center of the overlapping piece, additional pieces for covering the exposed joints between abutting ends, means extending through said pieces for securing the same together, and spacing members secured between the assembled strips and adapted to abut against the ends of the joint covering pieces.

2. Structural frame work comprising a plurality of assembled strips extending in one direction, each strip comprising a plurality of abutting and overlapping pieces so arranged that the joint between abutting ends occurs substantially at the center of the overlapping piece, spacing members secured between the assembled strips so as to form a plurality of rectangular caissons and X-shaped braces secured in said rectangles.

3. A frame comprising a plurality of assembled strips extending in one direction, each strip comprising a plurality of abutting

and overlapping pieces so arranged that the joint between abutting ends occurs substantially at the center of the overlapping piece, additional pieces for covering the exposed joints between abutting ends, means extending through said pieces for securing the same together, and spacing members secured between the assembled strips and adapted to abut against the ends of the joint covering pieces so as to form a plurality of rectangular caissons and cross braces secured in said rectangles on the opposite side of the spacing member from that abutting against the joint covering pieces.

4. A frame work comprising a plurality of assembled strips extending in one direction, each strip comprising a plurality of abutting and overlapping pieces so arranged that the joint between abutting ends occurs substantially at the center of the overlapping piece, additional pieces for covering the exposed joints between abutting ends, means extending through said pieces for securing the same together, spacing members secured between the assembled strips and adapted to abut against the ends of the joint covering pieces, so as to form a plurality of rectangles, cross braces located in the rectangles that do not contain the joint covering pieces, and tie bolts extending between the assembled portions and parallel to the spacing strips.

5. Structural frame work comprising a plurality of assembled strips extending in one direction, each strip comprising a plurality of abutting and overlapping pieces so arranged that the joint between abutting ends occurs substantially at the center of the overlapping piece, each of said pieces being of much greater length than depth, spacing members between said strips, alternately arranged lateral braces between said spacing members, and securing means for said strips, spacing members and braces, so that all stresses and strains are transmitted laterally through the frame work.

6. Structural frame work adapted to have the form of an arch without upright braces, said frame work comprising a plurality of assembled strips extending in one direction, each strip comprising a plurality of abutting and overlapping pieces, each of said pieces being of much greater length than depth and having one of the longer edges shaped on the arc of the particular arch to be formed, and the ends of said pieces being cut on a radius of said arc, means for securing said pieces together, and spacing members secured between the assembled strips.

In testimony whereof I affix my signature.

JULES LOUIS BADEL.
